UNITED STATES PATENT OFFICE.

CHARLES H. RICHARDS, OF AURORA, ILLINOIS, ASSIGNOR OF ONE-HALF TO RICHSTO MANUFACTURING COMPANY, A CORPORATION OF ILLINOIS.

METAL FACING FOR WINDOW OPENINGS.

Application filed January 30, 1926. Serial No. 84,385.

This invention relates to improvements in metal facings for window openings and is here shown as applied to a window opening.

One of the objects of my invention is to provide a smooth, neat, strong and durable protecting facing for window openings on the inside of rooms. The facing when installed, with the plastering in place, has the appearance of being a continuation of the plaster. The outer edge of the casing constituting the trim is spaced away from the wall substantially the thickness of the plaster, so that it will lie flush with the finished surface of the plaster and serve as a finishing ground therefor.

Another object of my invention is to provide a facing of the kind described which can be easily assembled and installed on the job.

Other features and advantages of my invention will appear more fully as I proceed with my specification.

In that form of device embodying the features of my invention, shown in the accompanying drawings, Figure 1 is a view in front elevation of my improved metal facing, Fig. 2 is a vertical sectional view taken as indicated by the line 2 of Fig. 1, Fig. 3 is a view taken as indicated by the line 3 of Fig. 1, and Fig. 4 is a fragmentary view of the upper part of a facing showing a modified form.

As shown in the drawings, the casing, in the preferred form, comprises an upper and a lower half of substantially the same shape and size. In Fig. 1 the upper half is indicated in general by A and the lower half by B. Since each of these pieces is substantially the same in construction, and adapted to be installed in the same manner, I will describe in detail but one. Each of these pieces comprises a single integral strip or piece of curved sheet metal substantially L-shaped in cross-section and bent in the form of a U.

Each of these pieces A and B may be pressed and formed out of a single strip of sheet metal, or the straight portions may be formed separately and the curved corners made out of separate pieces and joined to the straight portions. In the event, separate corner pieces are used in the manufacture, they should be soldered, welded or otherwise joined to the straight pieces so

that when completed the whole piece A or B is virtually one solid integral piece.

As stated above, each of the sheet metal pieces is L-shaped in cross-section as best shown in Figure 2. The inner face 10 forms the reveal and the outer face 11 forms the trim. The reveal 10 and trim 11 are joined by the curved part 12. In the lower half B of the casing, the reveal 10 is sometimes referred to as the stool.

The outer margin 13 of the trim 11 is bent inwardly and back on itself to form a U-fold to afford a horizontal groove 14 which faces inwardly. Suitable anchoring clips 15, also U-formed, are provided for attaching the casing to the wall. The shorter end of each of these clips is slidably mounted in the groove 14, and the longer end is adapted to be placed against the wall 16 and attached in any suitable manner as by means of the nail 17. The clips not only anchor the casing to the wall and maintain a suitable space between the trim and the wall, but are also spaced apart sufficiently themselves to permit the plastering or other filling 18 to be inserted between the trim and the wall. The extreme outer edge of the trim 11 as indicated by 11^a where the same is curved to form the bent back marginal portion 13, is flush with the plastered wall 18 and acts as a finishing ground for the plaster.

The bent back marginal portion 13 is also preferably provided with a longitudinal bend or corrugation 19 and the short end of the clip 15 is provided with a similar co-operating bend or corrugation 20, thus permitting the clip to slide longitudinally in the groove 14 but preventing it from being pulled out inwardly.

The portions A and B of the casing may be joined in any suitable manner and for such purpose, I have here shown the portion A as provided with two downwardly projecting tongues 21 adapted to be inserted in suitable sockets formed by the strips 22 on the part B.

In Fig. 1 it will be seen that the parts A and B of the casing are substantially the same shape and size, 23 indicating the junction of these two portions. In Fig. 4 I have shown a slight modification in which the portion A' resembling the portion A in the preferred form is considerably smaller, having its outer edge terminating at the junc-

tions 23'. In this modified form the lower portion B' is made with its vertical members correspondingly longer so as to reach to the junctions 23'.

5 While I have shown and described certain embodiments of my invention, it is to be understood that it is capable of many modifications. Changes, therefore, in the construction and arrangement may be made 10 without departing from the spirit and scope of the invention as disclosed in the appended claims, in which it is my intention to claim all novelty inherent in my invention as broadly as possible in view of the prior art.

15 What I claim as new, and desire to secure by Letters Patent, is:

1. A metal facing for a window opening comprising, two U-shaped integral metal pieces adapted to be placed together to form 20 a rectangular frame, each of such pieces being substantially L-shaped in cross-section to form a reveal and a trim.

2. A metal facing for a window opening comprising, two U-shaped integral metal pieces adapted to be placed together to form 25 a rectangular frame, each of such pieces being substantially L-shaped in cross-section to form a reveal and a trim, and means for attaching said pieces to a wall.

3. A metal facing for a window opening comprising, two U-shaped integral metal pieces adapted to be placed together to form 30 a rectangular frame, each of such pieces being substantially L-shaped in cross-section to form a reveal and a trim, and means for attaching said pieces to a wall and spacing the trim from the wall.

4. A metal facing for a window opening comprising, two U-shaped integral metal pieces adapted to be placed together to form 40 a rectangular frame, each of such pieces being substantially L-shaped in cross-section to form a reveal and a trim, and adjustable clips mounted on said pieces for attaching the same to a wall.

5. A metal facing for a window opening comprising, two U-shaped integral metal pieces adapted to be placed together to form 50 a rectangular frame, each of such pieces being substantially L-shaped in cross-section to form a reveal and a trim, and adjustable clips mounted on said pieces for attaching the same to a wall and spacing the trim away from said wall.

55 6. A metal facing for a window opening comprising, two U-shaped integral metal

pieces of substantially the same size and shape, adapted to be placed together to form a rectangular frame, each of such pieces being substantially L-shaped in cross-section 60 to form a reveal and a trim, and means for attaching said pieces to a wall.

7. A metal facing for a window opening comprising, two U-shaped integral metal pieces of substantially the same size and shape, adapted to be placed together to form a rectangular frame, each of such pieces being substantially L-shaped in cross-section 65 to form a reveal and a trim, and means for attaching said pieces to a wall and spacing the trim from the wall.

8. A metal facing for a window opening comprising, two U-shaped integral metal pieces of substantially the same size and shape, adapted to be placed together to form 75 a rectangular frame, each of such pieces being substantially L-shaped in cross-section to form a reveal and a trim, and adjustable clips mounted on said pieces for attaching the same to a wall.

9. A metal facing for a window opening comprising, two U-shaped integral metal pieces of substantially the same size and shape, adapted to be placed together to form a rectangular frame, each of such pieces being substantially L-shaped in cross-section 80 to form a reveal and a trim, and adjustable clips mounted on said pieces for attaching the same to a wall and spacing the trim away from said wall.

10. A facing for a window opening comprising a rectangular frame consisting of two U-shaped sheet metal members, each member being substantially L-shaped in cross-section to provide a reveal and a trim 85 at substantially right angles to each other, and means for joining said sheet metal members together.

11. A facing for a window opening comprising a rectangular frame consisting of 100 two U-shaped sheet metal members, each member being substantially L-shaped in cross-section to provide a reveal and a trim at substantially right angles to each other, the edges of the trim bent inwardly to provide a finishing ground for a plastered wall, and means for attaching said members to a wall and spacing the trim away from said wall.

In testimony whereof, I have hereunto set 110 my hand this 27th day of January, 1926.

CHARLES H. RICHARDS.
